GAME BOARD

Moises B. Lorenzana and Francisco B. Lemi,
Chicago, Ill.

Application November 9, 1949, Serial No. 5,946

Term of patent 14 years

(Cl. D34—5)

To all whom it may concern:

Be it known that we, Moises B. Lorenzana, a citizen of the Philippine Republic, and Francisco B. Lemi, a citizen of the United States of America, both residing in Chicago, county of Cook, and State of Illinois, have invented a new, original, and ornamental Design for a Game Board, of which the following is a specification, forming part thereof.

Figure 1 is a top plan view of a game board embodying our novel design;

Figure 2 is a side elevation, broken away at one end, looking from the bottom of Figure 1;

Figure 3 is an end elevation of the device shown in Figures 1 and 2; and

Figure 4 is a transverse sectional view along the line 4—4 of Figure 1.

We claim:

The ornamental design for a game board, as shown and described.

MOISES B. LORENZANA.
FRANCISCO B. LEMI.
